UNITED STATES PATENT OFFICE.

NORBERT LOCHBAUM, OF BERLIN, GERMANY.

DESIGN FOR A PHOTOGRAPHIC ALBUM.

SPECIFICATION forming part of Design No. 19,720, dated March 25, 1890.

Application filed January 27, 1890. Serial No. 338,291. Term of patent 3½ years.

To all whom it may concern:

Be it known that I, NORBERT LOCHBAUM, a subject of the Emperor of Germany, residing at Berlin, in the Province of Brandenburg, 5 Prussia, have invented and produced a new and original Design for Photographic Albums, of which the following is a specification.

Referring to the accompanying drawings, Figure 1 is an outer side view of the album. 10 Fig. 2 is a view of the album spread open.

The leading feature of my design consists in the shape or outline of the album, the distinctive characteristic of which is it has one edge straight, and from one end thereof curves 15 around toward the opposite end, which end has two protruding curves and an inward curve between them.

The letter A designates the two covers of the album, which are joined at one edge *b* in the usual manner. Each cover has the same 20 shaped margin, edge, or outline as above described.

I claim—

A design for albums, substantially as herein described and shown. 25

In testimony whereof I affix my signature in the presence of two witnesses.

NORBERT LOCHBAUM.

Witnesses:

PAUL WANDERS,
ADOLF FURKAT.
